UNITED STATES PATENT OFFICE.

LUTHER L. KNOX, OF PITTSBURGH, PENNSYLVANIA, ASSIGNOR TO KNOX PRODUCTS COMPANY, OF PITTSBURGH, PENNSYLVANIA, A CORPORATION OF PENNSYLVANIA.

COMPOUND WALL STRUCTURE.

Application filed August 26, 1926. Serial No. 131,654.

This invention relates broadly to compound wall structures and more particularly to structures of this nature suitable for use in the manufacture of furniture or parts thereof, such as table tops, refrigerators, storage boxes, display cases, or the like, and especially where it is desirable to maintain a temperature difference on opposite sides of the wall structure.

10 As disclosed in my application, Serial No. 2,872, filed January 16, 1925, there is provided a compound wall structure embodying insulating material and covering material, the two materials being held in predetermined spaced relation by chaplets, spacers or the like, and the space between the materials being filled by a poured-in filling.

The present invention relates broadly to compound wall structures of this general nature, or suitable for use in the same general manner therein referred to, but has for one of its objects, the provision of an improved structure such that the necessity of utilizing separate spacing means is obviated. In this manner, there is provided a structure capable of being more easily assembled.

Another object of the present invention is to provide an improved wall structure of such nature that a poured-in filling may be utilized but in which the amount of such filling may be maintained at a minimum, thereby lessening not only the cost of production while giving the desired results, but also materially lessening the weight of the finished structure.

In the accompanying drawings, there is shown for purposes of illustration only, certain preferred embodiments of the present invention, it being understood that the drawings are illustrative only and do not define the limits of my invention, as changes in the construction therein disclosed and the manner of making finished articles may be changed without departing either from the spirit of the invention or the scope of my broader claims.

In the drawings, Fig. 1 is a perspective view of one form of insulating body constructed in accordance with the present invention.

Fig. 2 is a transverse sectional view through a refrigerator constructed of insu-

lating bodies substantially as shown in Fig. 1.

Fig. 3 is the detail sectional view illustrating one manner of venting a compound wall structure during the pouring-in operation.

Fig. 4 is a vertical sectional view on the line IV—IV of Fig. 3 looking in the direction of the arrows.

Fig. 5 is a detail sectional view on the line V—V of Fig. 4 looking in the direction of the arrows.

Fig. 6 is a detail sectional view illustrating one manner of supplying the poured-in filling.

Fig. 7 is a top plan view of one form of preformed insulating body adaptable for use as illustrated in Figs. 1 to 6 both inclusive.

Fig. 8 is a side elevation of the insulating body shown in Fig. 7.

Fig. 9 is an end elevation of the insulating body of Figs. 7 and 8.

Fig. 10 is a view similar to Fig. 2 illustrating another embodiment of the invention.

Fig. 11 is a vertical sectional view, partly in elevation, showing still another embodiment of the invention; and,

Fig. 12 is a partial transverse sectional view on the line XII—XII of Fig. 11 looking in the direction of the arrows.

In accordance with the present invention, there may be utilized insulating material of any desired nature, but in view of its lightness, high insulating properties, and ease of handling, preformed cork board may be used to advantage. In Figs. 1 to 9, of the drawings, I have illustrated pre-formed insulating material preferably in the form of slabs or sections 2 of such dimensions as to facilitate handling thereof and subsequent assembly.

Each of the slabs may be constructed as clearly shown in the drawings, be any desired thickness, and with either longitudinal grooves 3, or transverse grooves 4, or both, in either or both of the main faces thereof, and with beveled sides, edges, or corners 5. Preferably the grooves in the respective sections are so formed that upon assembly they will cooperate either with corresponding grooves in the other sections or with the beveled sides, edges or corners, to provide

continuously extending zones of such nature that material poured into one of said zones at any point may flow into and fill all of said zones. Such a construction is clearly indicated more or less diagrammatically in the perspective view of Fig. 1.

While cork board, as well as other insulating bodies, possesses the necessary properties with respect to the transmission of heat therethrough, it is not possible to utilize such bodies alone for insulating purposes. This is true not only by reason of the susceptibility of such material to destruction from natural use and wear, but also by reason of the tendency of moisture laden air to circulate therethrough and there around with a resulting precipitation and subsequent freezing of the moisture content in such manner that in a short time the material loses any insulating properties.

In accordance with the present invention, it is desired to produce a compound wall structure having insulating properties which are substantially permanent whereby such structures may be maintained in continued use for long periods of time. To this end, the insulating body has at least one and preferably both faces thereof protected and substantially encased by a covering body 6, which covering body may comprise sheet metal or any other desired material. As illustrated in Fig. 2 of the drawings, the inner covering body has the different portions thereof so connected at the corners as by welding, lock-seaming, or the like to provide a substantially continuous lining, Fig. 2 indicating a portion of a structure suitable as a household refrigerator or the like.

In this embodiment, there is shown a framing strip 7, adapted to form an abutment for the doors not shown, and a reinforcing and door-carrying strip 8. The inner lining preferably extends continuously around the frame 7 and into a groove 9 in one of the strips 8. It may be held in position therein in any desired manner as by a locking strip 10. The outer covering may similarly extend continuously around the strips 8 and into grooves 11 therein which are so constructed as to receive other locking strips 12.

After the desired number of sections have been assembled and the covering body has been applied thereto, the structure is ready for the reception of a poured-in filler. Preferably this filler is of such nature as not only to prevent air circulation but also to tend to bind the insulating body and covering body together. I have found that natural or artificial asphalt or similar material may be advantageously utilized for this purpose, such material remaining at all times in a semi-solid condition and imparting sound deadening characteristics to the completed structure. By reason of the co-

operating relation of the various grooves in the insulating body, it is only necessary to supply the filling material at one point. As the zones provided by the grooves are filled, however, it is essential that means be provided for permitting the escape of the air which would otherwise be entrapped, to thereby permit complete filling of these zones, it being obvious that the air must be released from substantially the top point of the structure in the position which it occupies during the filling operation.

In Figs. 3, 4, and 5 there is illustrated in detail a suitable form of vent for permitting the release of air. This vent may comprise an outlet pipe 13 extending through a suitable opening in the covering body 6 and threaded into a reinforcing plate 14 secured in any desired manner to the covering body. The insulating body adjacent the plate 14 is cut away to permit the insertion of a casing 15 which may be welded in position by means of the flanges 16 thereon. This casing preferably has an open corner 17 communicating with the beveled edge of the insulating body to permit the free passage of air into the case and thence to the outlet pipe 13. The outlet pipe may be located in one of the upper corners of the completed structure and after removal of the outlet pipe the opening may be effectively sealed in any well known manner.

In Fig. 6 there is indicated an outlet pipe 16 extending through a suitable opening in the covering body 6 and threaded into a plate 17 similar to plate 14 before described. The cork adjacent this inlet pipe may be cut away to provide a distributing header 18 as illustrated in Fig. 7 connected by channels or grooves 19 with any of the grooves 4 formed in the insulating body. This will permit the passage of the filling material directly to the zones to be filled and thence throughout the entire structure. Where asphalt is the material utilized, it will be apparent that it will be poured in under such temperature conditions as to flow freely, and under sufficient head to insure filling of all of the zones provided therefor. The pouring operation will be continued until the filling material rises into the air outlet pipe 13.

In the event the insulating body has imperfections therein or is spaced slightly from the covering body, the poured-in filling will fill such voids or spaces thereby providing a tight joint between the respective bodies and preventing any circulation of air. In the event any air remains between the covering bodies, it will be pocketed between adjacent zones of poured-in filling in such manner that dead air spaces will necessarily result.

It will be apparent to those skilled in the art, that by the use of a grooved insulating body, it is unnecessary to provide chaplets

or other spacing means between the insulating body and the covering body. It will further be apparent that it is only essential in a structure of this general nature that 5 one of the bodies shall have portions thereof out of the plane of the remainder in order to provide zones for the reception of a filler, and instead of providing grooves in the insulating body, the covering body may be 10 so constructed as to serve the same function.

In Fig. 10 of the drawings, there is illustrated an insulating body 2' composed of sections which may have ungrooved faces, this insulating body cooperating with a covering body 6' having ribs, corrugations, depressions, or the like 20 formed therein in such manner as to insure the desired spacing and provide zones 21 for the reception of the poured-in filler. Communication between the inner and outer zones may be 25 established in any desired manner either by the provision of an opening (not shown) through the insulating body at any desired point, or by directly feeding the filling material to both sides of the insulating body. With the form of the invention illustrated in Fig. 10, the amount of poured-in filler will be materially greater than that present in a structure of the character shown for example in Fig. 2, since the poured-in filler 30 substantially completely covers the insulating body.

In other cases, as illustrated for example in Figs. 11 and 12, it may be desired to provide an insulating body 2' similar to that shown in Fig. 10 with a covering body 6'a of such nature that ornamental results are obtained. Such a covering body may, for example, have panels 22 of different shapes or 35 contours, formed therein and serving to provide zones 23 for the poured-in filler. The high spaces 24 between the panels will form connecting paths for the poured-in filler and communication with opposite sides of the insulating body may be established as referred to in connection with Fig. 10.

In Fig. 11, the inlet 25 is shown as extending completely through a portion of the insulating body and as having a channel 26 50 cooperating therewith for effecting the desired distribution of such filling material. The escape of air may in turn be permitted by an opening 27 extending through the insulating body from side to side thereof as 55 illustrated in Fig. 7, it being understood that such an opening will communicate with an outlet connection similar to that shown in Figs. 3, 4, and 5.

In my co-pending application, Serial No. 60 710,357 filed May 1, 1924, there is disclosed a compound wall structure in which the insulating material is provided with ribs serving to space the insulating material and the covering. Such ribs, however, require the 65 cutting away of a substantial portion of the

insulating material to permit their formation as therein shown and do not provide as effective an area of contact between the insulating material and the covering material as is provided where the insulating body 70 has comparatively small grooves therein forming zones for the poured-in filler.

The present invention provides a compound wall structure comprising an insulating body and a covering body in which at 75 least one of the bodies has portions thereof out of the plane of the remainder thereof to provide zones for the reception of a filler, and in which the desired spacing of the respective bodies results from the provision of 80 portions in different planes. One of the advantages of the invention arises from the provision of assembled bodies having such characteristics and obviates the necessity of 85 separate spacing means.

Other advantages of the invention arise from the possibility of materially decreasing the amount of poured-in filler required, and consequently the weight of the finished structure, by providing zones of relatively 90 small dimensions. Still other advantages arise from the provision of a finished structure capable of having any desired ornamental appearance imparted thereto by a 95 suitable construction of the covering body.

I claim:

1. A compound wall structure comprising an insulating body and a covering body for certain parts of said insulating body, at 100 least one of said bodies having portions recessed beyond the plane of the remainder thereof to provide zones for the reception of a filler.

2. A compound wall structure comprising an insulating body and a covering body 105 for certain parts of said insulating body, at least one of said bodies having portions recessed beyond the plane of the remainder thereof to provide zones for a filler, and a filler in said zones spacing the respective 110 bodies.

3. A compound wall structure comprising a pre-formed insulating body and a covering body for certain parts of said insulating body, at least one of said bodies having 115 interconnecting recessed portions beyond the plane of the remainder thereof to provide zones for the reception of a filler.

4. A compound wall structure comprising a pre-formed insulating body and a covering 120 body for certain parts of said insulating body, at least one of said bodies having interconnecting recessed portions beyond the plane of the remainder thereof to provide zones for a filler, and a filler in said zones 125 spacing said bodies.

5. A compound wall structure, comprising a sectional insulating body of pre-formed material, and a covering body for certain 130 parts of said insulating body, at least one

- of said bodies having portions recessed beyond the plane of the remainder thereof to provide zones for the reception of a filler.
6. A compound wall structure comprising an insulating body, a covering body for certain parts of said insulating body, at least one of said bodies having portions thereof out of the plane of the remainder thereof to provide zones for the reception of a filler, and means for permitting a filler to be poured into said zones.
7. A compound wall structure comprising an insulating body, a covering body for certain parts of said insulating body, at least one of said bodies having portions thereof out of the plane of the remainder thereof to provide zones for the reception of a filler, means for permitting a filler to be poured into said zones, and means for permitting the escape of air from said zones during the filling operation.
8. A compound wall structure, comprising an insulating body and a covering body cooperating therewith, at least one of said bodies being of irregular cross section to provide zones for the reception of a filler.

9. A compound wall structure comprising an insulating body having grooves formed therein, and a covering for a portion of said body.

10. A compound wall structure comprising an insulating body having grooves formed therein, a covering for a portion of said body, said body having at least certain of the edges thereof beveled.

11. A compound wall structure comprising an insulating body of pre-formed material having grooves extending in two directions formed therein, said grooves providing communicating zones for the reception of a filling material.

12. A compound wall structure comprising an insulating body and a covering body for certain parts of said insulating body, at least one of said bodies having portions intermediate the edges thereof disposed out of the plane of the remainder to provide zones for the reception of a filler.

In testimony whereof I have hereunto set my hand.

LUTHER L. KNOX.
